BALL STAKING MACHINE FOR PEN TIPS

Fred Ferber, Hohokus Township,
Bergen County, N. J.

Application January 10, 1947, Serial No. 721,389

3 Claims. (Cl. 113—32)

1

This invention comprises an improvement in staking machines, and more particularly a machine for movably securing or "staking" a spherical writing element in operative position at the end of a so-called "ball-point" pen.

The main object of the invention is to provide a ball-point "staking" apparatus having a movable carrier to bear a number of tips for such pens, parts or members for rotating the carrier and working the extremity of each tip in succession so that the ball will be properly seated therein; members for feeding the balls to the tips, and additional parts or members for treating the tips after the balls are inserted so that displacement of the balls is prevented while each ball is left free to revolve in the small cavity at the end of the tip which contains the ball.

Another object is to provide apparatus of the kind mentioned capable of operating with certainty and efficiency, and delivering a large output, and designed so that it is relatively simple in construction, comparatively small in size and embraces a minimum number of parts.

The nature and advantages of the invention are shown in the accompanying drawings, which illustrate a preferred embodiment of the improvement. I do not, however, wish to be limited to the precise structure disclosed herein, but the right is reserved to make changes consistent with the general principle of the apparatus and included in the meanings of the broad terms in which the claims are expressed.

On the drawings,

Figure 1 is a section on a plane extending from front to back of apparatus according to this invention.

Figure 2 is a section on line 2—2 of Figure 1. Figure 3 is a view partly in section of the delivery connections for the ball-staked tips.

Figure 4 presents a detail of the machine on a somewhat enlarged scale.

Figure 5 shows the member for actuating the carrier to move tips from one stage to another.

Figure 6 shows the end of the die for the final step of permanently confining the ball after it has been seated in the tip.

Fig. 7 also shows a detail of the machine.

Figure 8 shows another detail in section;

Figure 8a is a detail of a modification; and

Figure 9 is a top view and Figure 10 a section on line 10—10 in Figure 9 of a further detail.

The machine is made of a framework comprising a horizontal bed or foot 1 and an upright support 2 rising therefrom; and secured to the top of the bed 1 is a base 3 having a cylindrical

2

depression 4 therein to receive a carrier in the form of a circular disk 5. This carrier has a flange around its rim that overlaps the edge of the depression or seat 4 and it has a circular row of holes in it near the outer edge going through from top to bottom, and each holding therein a bushing or nipple 6. These nipples are perforated from end to end, and each has at its upper extremity a chamfered flange that rests upon the top surface of the carrier element 5; the opposite end of each nipple being flush with the bottom of the latter. The nipples 6 mount and hold the pen tips 7 during the operation of the machine, each tip, as indicated clearly in Figure 2, consisting of a cone-shaped head and a reduced neck, the latter fitting into the bore of the nipple and the shoulder at the junction of the head and neck resting on the flanged top of the nipple or bushing 6. The ball is inserted and imprisoned in the small outer end of the conical head of the tip. The tips 7 have a longitudinal bore or duct for the passage of ink therethrough. For convenience Figure 1 shows only part of the bushings 6.

25 The process of attaching the ball to the tip is carried out in three steps or stages, each of which involves the operation of a plunger assembly containing a punch-rod, as the nipples 6 and pen tips 7 move into position to be worked thereby. The plungers are actuated by a power medium that moves a piston in a cylinder 8 at the top of the machine mounted on the upright 2; the piston acting to depress a head 9 at the outer end of the piston rod 10 to strike all the plunger assemblies at one time. The carrier 5 is attached to a pivot screw stud 11 having a head at its lower end and turning in a bearing aperture at the center of the base 3, and counterbored at the bottom of the base to receive the screw. 30 The plungers are shown at 12, 13, and 15, the assembly 13 being associated with a transparent feeder 14, all mounted in vertical position and secured in a guide block 16 affixed to the base 3 at the rear, and projecting forward to overlap the carrier 5, but separated therefrom by a space 17.

35 The carrier is moved intermittently by an actuator elements having a push bar 19 affixed thereto, and disposed to slide back and forth in a guideway 20 in one side of the block 16. The element 18 is confined to the guideway 20 by a retainer plate 27, secured by a screw 28 to the side of the block 16. The part 18 is advanced and retracted by a cam plate 21, and the bar 19 acts by pushing each nipple in turn. At each

working stroke of the bar 19, moving tangentially of the carrier, the latter is revolved through an arc equal to the distance between the centers of the nipples 6. The cam plate is bolted to a yoke 22 having a threaded shank passing through a hole in a projection 24 on the piston head 9 and made fast by nuts 24. The plate 21 has an inclined cam-slot 25 that receives a pin 26 affixed to the element 18, all as shown in Figure 5. The push bar 19 is thus advanced at each upstroke of the piston rod 10. Each tip is carried first to the plunger assembly 12, where it is conditioned for the insertion of the ball, then to the assembly 13, where a ball is injected into it, and finally to the assembly 15, in which the smaller end of the cone-shaped head of the tip 7 is squeezed or contracted in minute degree to reduce the diameter of the opening to a width just less than that of the ball, and thus prevent the ball from falling out, while leaving it free to revolve in the tip 7. The piston is forced down by a power fluid, such as air, admitted at the upper part of the cylinder 8, and when the air is exhausted from the cylinder the piston therein is lifted as by a spring or by air admitted under it.

In the step by step rotation of the carrier 5, the latter is always brought to a stop with the nipples or bushings 6 and tips 7 in correct position beneath the assemblies 12, 13 and 15, by means of an index or controller plate or member 29, which is moved back and forth in a guideway 30 in the lower side of the guide block 16. The end of this plate is bevelled at both sides 31 in front, and has a width such that, when it is projected between two of the nipples 6 after each forward stroke of the push bar 19, its long axis will be midway between them, and it will thus hold the nipples so that the vertical axis of each is exactly in line with the vertical axis of the plunger assembly under which it is stopped. This effect is produced by the cam action of the symmetrical bevelled edges 31 at the front end of the plate 29. The plate 29 and guideway 30 are about at the center of the block 16. In its under side the element 29 has a longitudinal groove 32 that receives a projection on a plate or stop 33 affixed by a screw 34 to the rear of the base 3, and between said projection and the inner end of the groove 32 is a spring 35. This spring tends to project the element 29, but the latter has on its rear end a lug 36, that is united by a rod 37 suitably affixed thereto as by nuts 38 or otherwise, and passes through a hole 39 in the block 16 to the front thereof, where the rod 37 carries on its end a perforated split head 39' gripped on the rod by a screw 40. To the head 39 is affixed a sliding plate 41, mounted in a channel in the overhanging part of the block 16 and extending inward through a slot in the lower extremity of a tubular guide in the assembly 13. The element 29 is pushed back against the spring 35 by the cam action of the circular tops of the nipples 6 against the inclined corners or edges 31 at the end of said element. Every time the push bar 19 turns the disk, the element 29 is forced out of the way to allow a nipple to pass it. But the spring 35 immediately impels this element forward again and it always centers the end with the bevelled sides 31 between two adjacent nipples, thus getting them into the exact position required beneath the assemblies 12, 13 and 15. In the element or plate 41 is a hole 42 which is moved into alignment with the axis of the assembly 13 for a purpose to be explained later.

Each of the assemblies 12 and 15 comprises a

bushing 43 mounted in a bore in the block 16, said bushing having a shoulder 44 at the lower end to seat against an internal shoulder at the lower end of said bore. In the bushing 43 of the assembly 12 is a movable guide or plunger 45, having a collar 46 in the upper end of the bushing 43, and between this collar and the inner end of the bushing is a spring 47, surrounding the plunger and seated upon an internal shoulder at the inner end of said bushing. The plunger projects through the lower end of the bushing, and moves through a guide plate 48 affixed to the lower face of the block 16 by one or more screws 49. This plate has a curved groove 50, through which the tips 7 pass. The lower end of the plunger 45 has a recess shown at 51, and this recess is shaped to fit upon and envelop the cone-shaped head of the tip 7. This detail of the construction is more fully explained in the succeeding pages of this specification. It is sufficient to state here that the recess 51 should be shaped both to fit over the tip 7 and be wider at its outer end to engage the top of the bushing 6 also, and directly under the guide 45 the groove should be widened at each side, as indicated at 50' to allow the guide 45 to be depressed far enough.

The plunger or guide 45 has a central longitudinal bore therethrough, and within the bore is a punch rod or die 52, that has a reduced lower extremity 53. The bore of the plunger is also reduced at the lower end 54 to fit the extremity 53. The upper end of the bore 54 in the plunger is threaded and the rod 52 has a head 55 with a kerf for a tool, engaging said threads, a screw 56 being also used in the side of the plunger 45 to lock the pin in adjusted position. The rod or pin 52 on the down stroke of the head 9 is carried down with the plunger 45 and enters the small end of the cone-shaped head of the tip 7 in line with the axis thereof and shapes the end of the duct through the tip to finish the seat for the ball to be inserted into it. The seat is pre-formed in the tip but requires the rod 52 to complete it.

The tip is next carried beneath the plunger assembly 13, in front of which is a magazine or hopper 56 in which the balls are stored. This hopper has a stem 57 which is inserted at its lower end into a bore 58 in the block 16; and from the hopper 56 a duct 59 runs down through the stem and into a duct or passage 60 through the block 16 at the lower end of the stem 57 to the bottom of the injector assembly 13. The latter comprises a rod or pin 61 in a tubular bearing or guide 62 having a collar 63 which rests on the top of the block 16. The lower end of the guide 62 is exposed in the space 17 under the block 16. This bearing or guide has a bore running down through the center of it, as shown at 64 in Figure 8, the bore being reduced at the lower end and having a conical shoulder therein. The pin 61 also has a reduced lower end 65 to fit the reduced lower end 64' of the bore 64 in the bearing 62. On the top of the bearing 62 is a cap 66, and between this cap and the collar 63 is a coiled spring 67. The upper end of the rod 61 appears a fixed cross pin 68 which projects into slots 69 in the sides of the cap. The latter has a stud 70 inside which projects downward into the tubular guide 62, but is spaced from the upper end of the rod 61. The bearing or guide 62 also has longitudinal slots 71 in its upper end to give passage to the cross pin 68. The stroke of the head 9 comes at a time after one of the nipples or bushings 6 has just been moved directly into vertical line with

the rod 61, and during this movement the slide 41 is actuated so as to bring the opening 42, which has received a ball from the duct 60, directly beneath the pin 61. The ball fits the opening 42 loosely and before the slide 41 is returned by the spring 35, the ball in said opening drops into the reduced end 64' of the bore 64, below the slide 41 and is retained in the bore 64' by frictional contact. The head next depresses the cap 66 and finally the stud 76 engages the rod 61, so that the ball is pressed down into the end of the tip 7. When the head 9 is raised the spring 67 pushes up the rod 64', the pin 65 clears the opening, and the slide 41 is retracted by the spring 35 till the opening 42 again registers with the bore in the stem 57. The bearing or guide tube 62 is made secure by a binding screw 12 in the block 16. The guide 62 has a transverse opening 41a in its lower end for the plate 41, as shown in Figure 8.

The plunger or guide 45' of the assembly 15 has a large central bore 73, with a lower reduced portion 74 and a conical shoulder 75 in the lower end. It contains a sleeve 76, which also has a reduced shouldered lower extremity 77 (Figure 6) that projects into the still further reduced outlet 78 of the bore 74, below the shoulder 75. Above the sleeve 76 the part 73 of the bore opens through the top of the plunger 45' and has inside screw threads to receive an adjustable threaded head or nut 79, between which and the upper flanged end of the sleeve 76 is a spring 80. The sleeve 76 has a bore 76a through it to receive a rod 81 with a reduced shouldered end 82, and a reduced portion 83 at the lower end of the bore 76a. The rod 81 makes contact at its upper end with the nut 79. Between the portions 76a and 83 of the bore in the sleeve 76 is an inside shoulder 84 to lie adjacent the shoulder at the junction of the end 82 with the rod 81. The reduced part 83 of the bore in the sleeve 76 terminates in an expanding or flaring extremity 85. When each tip arrives in turn beneath the assembly 15 and the head 9 drives the plunger 45' down, the head carries the sleeve 76 and rod 81 with it. The rod 81 projects out of the sleeve 76, engaging the ball in the tip 7 and holding it in place, while the flaring end 85 of the bore 83 squeezes the end of the tip and makes the opening slightly smaller than the ball therein. The ball is thus prevented from falling out afterwards, but is still left free to roll in the tip.

After passing the plunger assembly 15, each nipple next registers with a duct 94 in the base 3 that is coupled to a conduit 95 leading to a valve casing 96. The casing is connected by a conduit 97 to a source of compressed air, and the valve casing is also joined by a conduit 98 to the cylinder 8. The valve in the casing has a rigid external arm 99 which is attached to a spring 100 anchored on the part 2 of the frame. From the arm a vertical link 101 drops downward to a pedal 102 under the base 3. When the pedal is depressed, the arm is pulled against the spring to turn the valve to open the conduits 98 to the piston 9 and to the duct 94. As the piston drives the member or head 9 down to the bushing 6 under it, the air blows the tip out of the bushing 6 in front of said bushing through a curved tube or delivery guideway 103, so that the tip 7 drops into a box or receptacle 104. The valve will have suitable passages to operate in this way, and need not be more fully described. The casing will also have an exhaust opening 105, and the passages in the valve will be so arranged that the spring holds the valve in such position that

when the conduit 97 is shut, the cylinder is open to the atmosphere, and the conduit 95 to the base 3 is cut off from the supply. When the pedal is depressed, the outlet 105 is shut and both conduits 95 and 98 put into communication with the supply pipe 97. A separate valve can be used for the conduit 95, with a part in the path of the head 9 to enable the conduit to be opened for the flow of motive agent to the duct 94 whenever the head 9 makes a downstroke, the valve in casing 96 remaining connected to the pedal 102.

The lower ends of both guides 45 and 45' are preferably shaped to fit the tops of the bushings 6 and the conical heads of the pen tips 7 mounted therein. Then as these plungers or guides are depressed upon the bushings and the pen tips, the tips and the plungers or guides are in correct operative position when the rods 52 and 81 are depressed. Preferably, for this purpose, the machine includes a pair of guide plates such as are shown at 86 and 87 in Figures 9 and 10. These two plates can be attached to the bottom of the overhanging part of the guide block 16 in the position shown by the plate 86 in the Figure 1, and similar plates can be secured under the guide 45'. The two plates have opposed curved faces which are separated from each other by a sufficient space to form a groove 88. This groove follows a circular arc which has the same radius as the arc which passes through the axes of the several tips 7 in the bushings 6. The sides of this groove will be parallel adjacent the upper faces of the two plates, said faces being in contact with the bottom of the overhanging part of the block 16. Adjacent the lower edges however, the walls of the groove will diverge downward and the slope and width of the groove adjacent the bottom faces of these two plates will be approximately the same as the slope and diameter of the coned heads of the tips 7. When these plates are secured in position each tip 7 can enter one end of the groove 88 and move around through this groove from one operative position to the next.

The two plates 86 and 87 thus make up a single guiding unit and they are recessed to present semi-circular spaces 89 to receive the lower ends of the plungers 45 and 45'. These semi-circular spaces extend cross-wise of the groove 88 and are fashioned partly in one plate and partly in another. The spaces are separated by projections 90, one on the plate 86, the other on plate 87, these two projections being in line and separated from one another by a distance equal to the width of the groove 88. The opposing ends of these projections have the same slope as the lower parts of the sides of the groove 88, and their tops slope downward towards each other, as indicated at 90a in Figure 10.

The guide, such as the guide 45' is shown in Figures 1 and 7 as having a transverse notch or recess 91 in its lower end and the ends 92 of this recess are beveled to correspond to the slope of the tops 90a of the projections 90. The sides of this notch 91 are recessed to provide a circular cavity 93 in the end of the guide of the same diameter as the top of the bushing 6, and also to form conical surfaces 72 at each side of the transverse notch or recess to fit upon the tip 7. Obviously if the two guide plates are supported so that the projections 90 will be in line with the notch 91 of the guide 45', whenever a bushing 6 is carried underneath the plunger assembly 15, for example, a down stroke 75 of the head 9 will depress the guide 45' to make

the lower end of this guide enter the recesses 89 in the guide plates 86 and 87. The bushings 43 and guides 45 and 45' will of course be secured against rotational shifting in the block 16, by any suitable means. This lower end will straddle the projections 90, because these projections will enter the opposite ends of the transverse slot 91 and the cavity 93 will fit down on the bushing 6. The tip 7 will then be between the projections 90 and between the conical recesses 1a at both sides of the notch 91 in the guide 45'. The pen tip 7 will thus be held firmly and in true position. If the guide plates are used in connection with the guide 45 the tip 7 will be exactly in line with the reduced end 54 of the rod 52, and when similar plates are used for the guide 45', the coned head of the tip 7 will be securely held in line with the rod 81, so that, when the guide is depressed the sleeve 76 will so engage the end of the tip carrying the ball therein, that the inside surface 85 at the lower end thereof will squeeze the end of the tip and make sure of confining the ball therein. While this is being done the reduced end of the rod 81 will rest on top of the ball to prevent displacement of it from the tip during the confining operation.

The cam 21 and yoke 22 can be offset to the rear, to give sufficient clearance, if necessary.

In Figure 8a the bearing 62 is shown as having the same shape as in Figure 8, but in the side thereof at the lower end is a recess 62' which opens through to the small part of the bore 64' in the lower end just below the opening 41a for the slide 41. In this recess is secured a spring 62a, one end of which is bent so that it will project slightly into the small part of the bore 64 just under the space 41a. Hence a ball for the tip of the pen is always retained in the guide 62, even if it drops a little below the slide 41 after this slide carries the ball from the stem 57 into the guide 62 and the opening in the slide registers with the bore through which this ball must pass to be seated in the tip 7. The bent inner end of the spring will keep the ball from dropping out of the guide 62, but when the rod 61 is depressed the reduced lower end thereof will drive this ball down and out of the end of the guide and into the pen tip, because the rod 61 will push the ball past the arresting end of the spring 62a.

The apparatus is thus well adapted to serve the purposes of the invention and gain all the objects thereof.

Having described my invention, what I believe to be new is:

1. Apparatus for confining balls in conical pen tips having concave seats comprising a rotatably mounted carrier disk having a circular row of equidistant holes therein, a bushing in each hole to receive a tip, a base supporting said carrier, a block on said base overlapping the carrier and having a space between it and the carrier, the latter being movable through said space, a plunger assembly mounted in said block adjacent said row, said assembly including a depressible guide projecting through the block and having a bore presenting an open end to the carrier, a

rod fixed in the guide, the end of said bore being shaped to fit upon the tip when the guide is depressed, the rod having its end within the bore, a second plunger assembly in the block and projecting through it including a guide fixed in the block, a depressible rod in said fixed guide, a magazine adjacent said second assembly, a tubular member connecting said magazine to the block adjacent the fixed guide, a slide member at the lower end of the said member in the block and passing through the second guide, said slide having a hole therein to receive a ball and carry it into line with a bore in the fixed guide to be forced by the rod out of said bore into the seat of the pen tip, a third plunger assembly in the block opening into said space, said third assembly including a depreseable guide having a spring pressed sleeve therein, and a rod passing through a bore in said sleeve, the lower end of the last-named bore being conical to fit over the pen tip and contract the tip while the last-named rod holds the ball in the seat, a head operable to engage all the plunger assemblies simultaneously, the assemblies being disposed at intervals according to the spaces separating said holes, means for actuating the carrier to move the bushings and tips step by step successively into line with each assembly, and spring engaged means in the block for stopping the carrier each time with the bushings in axial alignment with the plunger assemblies.

2. The apparatus of claim 1 in which the means for rotating the carrier include a diagonally slotted element connected to the plunger, a push rod to engage the bushings in succession, a cam block carrying the rod, a pin on said cam block uniting the block to said slotted element, said spring means in the block being joined to said slide to control the latter.

3. The apparatus of claim 1 wherein said block has guide plates under its overlapping part, said plates being separated by curved grooves in line with the tips.

FRED FERBER.
